GYRATORY CRUSHER

Joseph E. Kennedy, New York, N. Y., assignor to
Kennedy-Van Saun Mfg. & Eng. Corporation,
New York, N. Y., a corporation of Delaware

Application October 7, 1937, Serial No. 167,729

3 Claims. (Cl. 83—10)

This invention relates to crushers for reducing material, such as ore, rock and the like materials, and relates particularly to gyratory crushers embodying a gyratory crushing member and a fixed crushing member arranged in encircling relation to and spaced from the gyratory crushing member.

In gyratory crushers there is provided a frame consisting of a lower supporting frame member or shell adapted to be mounted and supported upon a suitable foundation, a one piece annular member or shell superposed to and supported from the lower frame member or shell, and a spider member having an annular portion whereby it is supported upon the annular frame member or shell with arms converging therefrom merging with an axial hub portion, the frame members being secured together in assembled position. The gyratory crushing member is suspended from one end in the hub of the spider member axially of the frame and mounted at the opposite end eccentrically in a bushing rotatably mounted in the lower member of the crusher frame concentrically thereof. The annular frame member or shell serves as a carrier for the fixed crushing member in the form of segments, commonly termed concaves, mounted on the inner face of said annular frame member or shell by a soft material relative to the hardness of the material of the concaves and carrier therefor interposed between the opposing faces of the concaves and annular shell. Should it become necessary to remove the crushing member or concaves from the shell due to wear and necessary to substitute a new crushing member or concaves or otherwise, it is necessary in order to remove the concaves or crushing member to fuse the material, such as zinc, filled in between the opposed faces of the concaves or crushing member and the shell or carrier therefor, and then a resetting of the new crushing member or concaves and filling of the material to hold the concaves to the shell or carrier between the concaves and shell. Furthermore, the gyratory movement of the gyratory crushing member or head in transmitting the crushing forces to the concaves tends to impart rotative movement to the concaves and a shearing of the material filled between the opposed faces of the concaves and carrier therefor. It is the object of the present invention to provide an improved construction and arrangement of the annular frame member or shell constituting the carrier for the crushing concave and an improved constructed and arranged crushing member or concave to overcome the above disadvantages by providing a one piece annular crushing concave or member and a separable sectional carrier shell for the crushing member or concave arranged with means to firmly draw the carrier to the crushing member or concave to

hold and support the same without filling a holding material for the crushing member or concave between the opposed faces of the crushing member or concave and carrier therefor whereby the crushing forces transmitted to the crushing member or concave will be transmitted directly to and taken up by the carrier as well as facilitating the mounting and dismounting of the crushing member or concave from its carrier.

Other objects and advantages of the invention will hereinafter appear.

In the drawings accompanying and forming a part of this application,

Figure 1 is a longitudinal sectional view of a gyratory crusher illustrating an embodiment of the invention.

Figure 2 is a side elevation, on an enlarged scale and partly in section, to show the connection of the carrier for the crushing member or concave with the lower frame member and spider member, the section being taken substantially on the lines 2—2 of Figure 3 looking in the direction of the arrows.

Figure 3 is a sectional view taken substantially on the line 3—3 of Figure 2 looking in the direction of the arrows.

Figure 4 is a plan view of the carrier for the crushing member or concave.

Figure 5 is a side elevation of the carrier for the crushing member or concave looking at the right of Figure 4; and

Figure 6 is a fragmentary sectional view to show the arrangement and supporting of the crushing member or concave by its carrier, the section being taken substantially on the line 6—6 of Figure 3 looking in the direction of the arrows.

An embodiment of the invention is shown in the drawings in connection with a gyratory crusher wherein the operative parts are mounted in a frame, comprising a lower supporting frame or shell member 6 adapted to be mounted on a suitable foundation and having an annular portion at the top, an upper frame member in the form of a spider having an annular portion 7 with arms 8 converging therefrom and merging in a hub portion 9 axially of the crusher frame, and a carrier for a crushing element interposed between said frame members. The frame members are secured together in assembled position by suitable means and shown as bolts or tie rods 10 extended through openings in the annular portion 7 of the spider member and a flange extending laterally from the top end of the main frame member or shell 6, the one end of the tie rods 10 being arranged with a head and nuts threaded onto the opposite end to draw the frame members together. A crushing head in the form of a mantle 11 is mounted on a core 12 carried on a conical portion of or integral with a shaft 13.

12, the mantle being retained on the core by a nut 13 threaded onto a sleeve retained on the shaft by a clamping collar fixed on the shaft and a lock nut, as at 14. The head carrying shaft 12 is suspended in the frame to have downward and upward yielding movement by loosely extending the upper end portion of the shaft through the hub portion of the spider and suspending the shaft from said hub by a collar 15 5 adjustably mounted on the end of the shaft resting on springs 16 circumferentially spaced about the shaft and supported on a collar 17 engaging a suspending ring or sleeve 18 within a bushing 19 in the hub and supported upon a wearing ring 15 20 supported in a socket in the spider hub 9. The sleeve 18 in the bushing 19 and said bushing are arranged to permit of gyratory movement of the shaft about the axis of the crusher frame. The opposite end of the shaft 12 is connected to driving means to transmit the rotary movement of the driving means to gyratory movement of the shaft and crusher head. The driving means is shown in a conventional manner at M as an electric motor the rotor of which is 25 rotatably supported by the frame independent of the shaft and operatively connected to the shaft through a sleeve rotatably mounted axially in the frame member 6 and in which sleeve the shaft is loosely engaged eccentrically of the axis 30 of the frame. The eccentric sleeve connection with the driving means is not shown since it does not constitute an essential feature of the present invention and is well known in the art. The carrier for the crushing member or concave 35 comprises laterally separable sections, shown as two substantially semi-circular sections 21, 22. Each of the sections 21, 22 is arranged at the ends with a portion of increased thickness and less length than the length of the sections to provide the same with outwardly extending reinforcing lug portions 23 having openings 24 extended therethrough and equidistantly spaced from the ends of the sections. The end faces of the sections are substantially flat with 40 portions extending transversely thereof through which the openings 24 are extended, as at 25, projecting slightly forward of the portions 26 intermediate and at the opposite sides of said portions 25. The sections 21, 22 are adapted to 45 be drawn toward each other and secured together by suitable means and shown as tie rods extended through the registered openings 24 in the sections with nuts threaded onto the projecting ends of the tie rods, as at 27, the intermediate portions 26 being provided with recesses or bores, as 28, adapted for the slidable engagement of alining pins 29. The opposite ends of the sections 21, 22 are externally reduced, as at 30, Figures 4 and 5, the reduced wall portion 30 50 at one end being adapted to have sliding engagement with an annular wall of an annular recess extended into the corner of the end wall and inner face at the top of the bottom frame member 6, as at 31 in Figures 1, 2 and 6, and the reduced wall portion at the opposite end of the sections 21, 22 adapted to have sliding engagement with an annular wall of an annular recess in the annular wall portion of the spider member, as at 32. The reduced wall portions 30 55 at the opposite ends of the sections 21, 22 are preferably slightly inclined inwardly to the ends of the sections, and the walls 31, 32 of the recesses in the top of the lower frame member or shell 6 and the annular portion 7 of the spider member are correspondingly formed, whereby the 75

wall 30 at the lower end of the sections 21, 22 will firmly engage the recess wall 31 in the lower frame member 6, and the wall 32 of the recess in the annular portion 7 of the spider member will firmly engage the wall 30 at the upper end of the connected sections 21, 22. The sections 21, 22 are arranged with a recess in the corners at the opposite ends and inner face thereof with the one wall extending parallel to the axis of the sections, as at 33, for a purpose hereinafter described.

Each of the sections 21, 22 is arranged intermediate the ends of increased thickness to reinforce and strengthen the sections and provide the sections with an inwardly projecting arcuate portion midway the ends the face of which arcuate portions is flat and extends substantially parallel to the axis of the sections, as at 34.

The crushing concave comprises an annular member 35 of wear resisting material, such as manganese steel, said crushing member being of a length substantially equal to the length of the carrier sections 21, 22. The one face of said crusher concave and constituting the crushing face is arranged with a portion 36 intermediate the ends extending substantially parallel to the axis thereof, and the portions of said face at the opposite ends of said portion 36 being preferably of the same length and diverging at substantially the same angle from said intermediate portion 36 to the ends of said member, as at 37.

The crushing member or concave 35 carried by the carrier sections 21, 22 is substantially of uniform thickness. At the opposite ends it is arranged with an annular rearwardly extending flange adapted to engage in the recess 33 at the corners of the inner face and opposite ends of the sections 21, 22 with the peripheral wall extending substantially parallel to the axis of the crushing concave and engaging the arcuate wall of the recesses 33 and thereby supporting the crushing member or concave 35 at the ends by and in contact or engagement with the carrier sections 21, 22. A portion of the crushing concave extending rearwardly from intermediate the ends thereof and opposite the portion 36 of the crushing face is adapted to engage directly with the face 34 of the inwardly projecting portion 34 of the sections 21, 22, as clearly shown in Figures 2 and 6.

The face of the mantle 10 of the crushing head is arranged to form in conjunction with the portions 36, 37 of the crushing face of the crushing concave 35 a crushing chamber tapering downwardly the angle of the crushing faces of which chamber decrease progressively downwardly from the top or inlet end to the bottom or outlet end of the crushing chamber and said bottom end diverging outwardly from the axis of the crusher.

To center the crushing member or concave in the carrier sections 21, 22 when assembling the same, centering pins are provided and adapted to engage in recesses or bores in the faces 34 of each frame section 21, 22 midway the ends thereof and in recesses or bores arranged diametrically opposite in the portion of the crushing concave 35 opposed to the portion 34 of the carrier sections 21, 22, as shown at 38 in Figures 3 and 6.

To further reinforce and strengthen the sections 21, 22 each of said sections is provided with outwardly extending portions 39 spaced longitudinally midway the ends of the sections, as shown in Figures 3, 5 and 6.

The crushing member or concave 35 may be

assembled in the carrier sections 21, 22 prior to mounting the same in the crusher frame when said assembled unit is assembled in the lower frame member 6 by engaging one reduced end 30 of the assembled sections in the recess in the top of the lower frame member with the face of said reduced portion 30 engaging the outer wall of said recess when the spider member is mounted on the assembled sections 21, 22. To facilitate mounting of the crusher concave 35 assembled in the sections 21, 22 upon the lower frame member 6, one of the sections 21, 22, or both of said sections, and shown as the section 21 in Figure 4, is arranged with a laterally extending projection 40 adapted for connection thereto of a cable or chain of a hoisting means. It will be obvious that by loosening the nuts 27 on the tie rods connecting the sections 21, 22 that the crushing member or concave 35 may be readily removed therefrom to reverse the position of the crushing member or concave or to substitute another crushing member or concave, and that said sections 21, 22 may be drawn into firm engagement with the reinforcing flanges at the ends of the crushing concave and the laterally extending portion intermediate the ends thereof and thereby rigidly support the crushing member or concave. To assure intimate and firm engagement of the crushing member 35 with its carrier sections the outer wall of the recesses 33 and the face of the reduced portions at the ends of the sections 21, 22, as well as the face of the flanges at the opposite ends and intermediate portion of increased thickness of the crushing member or concave are machined or ground. The recess in the annular portion of the spider member and the annular recess in the top of the bottom frame member or shell are of the same diameter, and the reduced outer portions 30 at the ends of the sections 21, 22 circumscribe a circle having a diameter substantially the same as said recesses 31, 32 in the bottom frame shell and spider member whereby the sections 21, 22 may be reversed end to end between the lower frame shell and spider member.

Having described my invention, I claim:

1. In a gyratory crusher, a frame including a lower frame member having an annular upper end wall and a spider member having an annular wall portion at the lower end, said annular portions of said frame and spider members having like recesses extended into the inner face and end thereof, an annular member comprising laterally separable sections removably mounted and supported in the lower frame and spider members with the ends engaging in the recesses in the annular wall of said frame and spider members, each section of said annular member having like arcuate recesses of angular form in cross section extended into the inner face and ends thereof with one wall of the recesses of angular form arranged concentric of the annular member, and each section having an inwardly projecting portion midway the ends the inner face of which is arranged in an arc having a radius less than the arcuate wall of the recesses, and an annular crushing member adapted to be clamped and supported within said sections of the annular member having outwardly projecting portions at 70 and intermediate the ends thereof in engagement with the arcuate face of the inwardly pro-

jecting portion and the recesses to support the crushing member within the sections of said annular member.

2. In a gyratory crusher, a frame including a lower shell having an annular wall portion at the top with a recess of angular form in cross section extended into the top and inner face thereof with the outer wall of the recess diverging outwardly, and a spider member having an annular wall portion with an annular recess of angular form in cross section extended into the end and inner face thereof with the outer wall of the recess diverging outwardly, a pair of releasably connected and laterally separable sections of semicircular form having a portion at each end arranged to conform with and engage the diverging wall of the recesses in the top of the lower shell and annular wall portion of the spider member to mount and support said sections in and between the lower shell and spider member, and each of said sections arranged with a recess extended into the ends and inner face thereof and having an inwardly projecting portion midway the ends arranged with an arcuate face having a less radius than the recesses in the ends and face of the sections, means to draw the spider member to the lower shell and clamp the separable sections between the same, a one-piece annular crushing member arranged with a face having a portion intermediate the ends of uniform diameter and an annular portion projecting outwardly from the rear of said portion of the face adapted to engage the annular face of the inwardly projecting portion of the sections of the annular member, and portions of said face diverging outwardly from said intermediate portion to the ends of the crushing member arranged with rearwardly extending flanges at the ends adapted to engage in the recesses in the face and ends of the sections of the annular member to support the crushing member from said sections, and a crushing member within the annular crushing member supported in the frame to have gyratory movement relative to the annular crushing member. 45

3. In a gyratory crusher, a lower supporting frame member, an upper spider member, an annular member comprising laterally separable sections removably supported by and between said lower frame and spider members, said sections each having arcuate recesses in the inner face at the opposite ends forming a continuous circular recess in the assembled sections, and each section having an inwardly projecting portion substantially midway the ends arranged with an arcuate face forming a continuous circular face in the assembled sections having a radius less than the end recesses, and a one piece annular crushing member the face of which is arranged of uniform diameter intermediate the ends and portions diverging outwardly from said intermediate portion to the opposite ends, and said crushing member arranged with outwardly extending annular portions at the opposite ends and midway the ends adapted to engage and support the crushing member from the recesses in the ends of the sections of the annular member and the inwardly projecting portion midway the ends of said sections. 65

JOSEPH E. KENNEDY. 70
